UNITED STATES PATENT OFFICE.

RAPHAL AIZENMAN, OF NEW YORK, N. Y.

EASEL FOR SUPPORTING AND EXHIBITING PHOTOGRAPH-ALBUMS.

SPECIFICATION forming part of Letters Patent No. 627,792, dated June 27, 1899.

Application filed March 11, 1899. Serial No. 708,624. (No model.)

To all whom it may concern:

Be it known that I, RAPHAL AIZENMAN, a citizen of the United States, residing in the borough of Manhattan, city of New York, and 5 State of New York, have invented certain new and useful Improvements in Easels for Supporting and Exhibiting Photograph-Albums, of which the following is a specification.

This invention relates to an easel for supporting and exhibiting photograph-albums, 10 the object of the invention being to so construct the easel as that the parts thereof will fold or that they can be shifted into more convenient or smaller compass.

15 The invention consists of certain features of construction and combinations of parts to be hereinafter described and then claimed.

In the accompanying drawings, Figure 1 is a perspective view of my improved easel, 20 showing an album supported in position thereon. Fig. 2 is an enlarged vertical transverse section of the easel, the handle portion being broken away. Fig. 3 is a vertical transverse section of the easel in collapsed or folded position; and Fig. 4 is a transverse section on the line 4-4, Fig. 2, looking upwardly.

Similar letters of reference indicate corresponding parts.

Referring to the drawings, A represents 25 the side standards or legs of the easel, which are connected together by means of a handle portion B, that is strapped or braced thereto in any suitable manner at b, so as to provide in the upper ends of the tubular side standards A sockets a, into which the arms C', which are pivoted to one of the covers of the 35 album C, are inserted. The album C, when connected, as described, with the supporting frame A of the easel, rests with its back upon

40 a shelf portion now to be described. The shelf portion consists of a box-section E, which is pivoted at e to the side standards A, near their lower ends, the pivots e being located nearer the forward end of the box-section E than its rear end. The box-section E is arranged to coöperate with a lower box-section F, which is connected at a point near its forward end by means of laterally-extending studs or guide-pins f with the slotted 45 lower ends A' of the side standards, said studs or pins f being guided in the slots a' in such a manner as that when the box-sections are

50 moved together into the position shown in Fig. 2 they are moved inwardly one upon the other, so that the box-section E is arranged above the box-section F. The box-sections are connected together, as presently to be described, in such a manner as that when the easel is lifted by taking hold of the handle portion B the said box-sections will slide outwardly one upon the other and be turned into the position shown in Fig. 3, where they are approximately in line with the side standards A, thereby collapsing the structure. The box-sections are connected with and 55 guided upon one another by means of guide-lugs G on the inner wall of the box-section E, which guide-lugs are adapted to move in longitudinal slots g in the inner or adjacent wall of the lower box-section F, said lugs being connected by means of a cross-bar H and being also connected, by means of suitable tension-springs h, with the adjacent end of the box-section F. The upper box-section E may contain a drawer E', while the lower box-section F serves as a sort of secret compartment inasmuch as it is provided with a spring-actuated door F'. When the parts are moved 60 into the position shown in Fig. 1, the weight of the album resting upon the forward end 65 of the box-section E holds the parts in their using position, while when the album is removed and the easel lifted by means of the handle portion the parts under the actuation of the tension-springs are caused to automatically assume the position shown in Fig. 3. In this manner a unique and serviceable 70 construction is provided, which at the same time serves for both supporting the album and for compartments for containing papers, 75 photographs, &c.

I do not limit myself to the precise construction of the box-sections shown in the drawings, and it is evident that it is within the scope of any skilled mechanic to construct said box-sections of oblong instead of triangular or any other desirable cross-sections. It is also evident that it is within the scope of my invention to connect the box-sections in any other suitable manner.

Having thus described my invention, I claim as new and desire to secure by Letters Patent—

1. In an easel for supporting and exhibit-

ing photograph - albums, the combination, with a supporting-frame, of a shelf portion, movably connected with said supporting-frame, and composed of sections movable one 5 relatively to the other, whereby the parts are adapted to be folded or collapsed, substantially as set forth.

2. In an easel for supporting and exhibiting photograph-albums, the combination of 10 the supporting-frame, a box-section pivoted to said supporting-frame, and another box-section, guided along said supporting-frame, and provided with means for guiding it along the first box-section, substantially as set forth.

15 3. In an easel for supporting and exhibiting photograph-albums, the combination of a supporting-frame, provided with slots, a box-section pivoted thereto, another box-section provided with studs guided in said slots,

and means for guiding said box-sections one 20 upon the other, substantially as set forth.

4. In an easel for supporting and exhibiting photograph-albums, the combination of a supporting-frame, a box-section pivoted to said supporting-frame, another box-section 25 suitably connected with said supporting-frame, means for guiding the box-sections one upon the other, and a spring connecting the box-sections for automatically collapsing all of said parts, substantially as set forth. 30

In testimony that I claim the foregoing as my invention I have signed my name in presence of two subscribing witnesses.

RAPHAL AIZENMAN.
